W. A. LAUFER AND A. KUFTA.

SASH LOCK.

APPLICATION FILED JUNE 15, 1921.

1,429,891.

Patented Sept. 19, 1922.

UNITED STATES PATENT OFFICE.

WILLIAM A. LAUFER AND ANDREW KUFTA, OF PATERSON, NEW JERSEY.

SASH LOCK.

Application filed June 15, 1921. Serial No. 477,637.

To all whom it may concern:

Be it known that we, WILLIAM A. LAUFER and ANDREW KUFTA, citizens of the United States, residing at Paterson, in the county 5 of Passaic and State of New Jersey, have invented certain new and useful Improvements in Sash Locks, of which the following is a specification.

This invention relates to sash locks and 10 particularly to sash locks of the class in which the parts are secured upon the top surfaces of the meeting-rails of the two sashes, and its principal object is to provide a sash-lock which will automatically lock 15 the two sashes when, one being already fully closed, the other is moved to the fully closed position, and which will furthermore be proof against unlocking except at the inside of the window or other opening closed by 20 the sashes and by the means which is provided for that purpose.

In the drawing,

Figure 1 is a side elevation of the improved sash-lock, its parts being shown arranged on the meeting rails (appearing in section) of two sashes, one of which is partly open;

Figure 2 is a similar view, both sashes being in closed position and locked by the 30 sash-lock;

Figure 3 is a vertical sectional view of the sash-lock;

Figures 4 and 5 are plan views of the main parts of the device; and

Figure 6 is an inside view of the part forming the member B.

a designates the lower or inner sash and *b* the upper or outer sash of a window, *a'* and *b'* being respectively their upper and lower 40 (that is to say, their meeting) rails.

On the top surfaces of these rails we secure the members A and B, the member A on the rail *a'* and the member B on the rail *b'*; we term the members A and B inner and 45 outer members, respectively.

Member A includes a base-plate *c* and, upstanding therefrom, a pair of parallel standards *d*, whose upper ends overhang outwardly somewhat, that is toward the 50 sash *b* when said member has been secured upon the rail *a'*, as by screws passed through suitable holes in its base-plate and driven into said rail. In the preferred construction the outer edges of the standards are formed 55 to rise approximately vertically for a suit-

able distance, as at *f*, and then pitch forward at an incline and being also slightly convex, as at *g*, the purpose of which will appear hereinafter. In the upper ends of the standards is formed a pair of alined holes *h*, 60 which are approximately, at least, alined with the vertical edge portions *f* of the standards. On a pin in these holes is fulcrumed a locking lever or pawl, the same including a hook *i* which depends from the fulcrum of said lever or pawl and an inwardly projecting operating arm or handle *j* which is long enough to project inward beyond the rail and is adapted to rest on the base-plate *c*. In the position of the pawl 70 or lever shown in full lines in Figs. 1 to 3, where its arm or handle rests on the base-plate *c*, the front edge *k* of the shank of its said hook *i* is pitched upward and outward and the top edge *l* of the catch or hook-proper of its said hook is inclined upward and outward at a less angle forming a hooking face, the edges *k* and *l* forming a V-shaped notch whose apex is about coincident with the plane of the vertical edges *f* of the standards *d*, that is, approximately vertically beneath the holes *h*. The catch or hook-proper is preferably rounded at the under side, as at *m*.

Member B includes a base-plate *n* and upstanding therefrom a hook *o* which rises from the outer portion of the top surface of the base-plate, which latter is adapted to be secured to the rail *b'* by screws passed through suitable holes therein. The hook 85 is fairly broad and its hook-proper projects inwardly. The catch shoulder or hook-proper of this hook has an inner cam face *q* pitched inward and downward and also formed concave in substantial conformity 90 with the convex face *g* of the standards *d* of the member A, and an under hooking face *r* inclined inward and downward at a less angle, said faces giving the catch or hook-proper a wedge shape in side elevation somewhat more acute than the V-notch of the pawl hook *i*. Formed integrally with the base-plate *n* and hook *o* is a pair of spaced upstanding lateral walls or webs *s* which with the base-plate and hook form a housing 95 that is open only inwardly, the front edges *t* of these walls being vertical and so conforming with the vertical edges *f* of the standards *d* of member A.

As viewed in front elevation, Fig. 6, it 110

will be preferable to flare the top portion of the aforesaid housing, for a purpose to be explained.

Assuming either sash to be closed, if the other be moved to closed position the pawl or lever will be cammed back by the face *q* of member B and having passed said face will return to the normal position (Fig. 2) and interlock both sashes so that neither can be opened without moving the pawl so that its hook will again clear the hook of member B. The handle *j* by its weight of course holds the pawl in the locking position, and it affords means for readily releasing the pawl.

15 The device can not be tampered with by implements entered between the sash rails from the outside, because the pawl is protected from manipulation in that way by the walls *s*, by the devious form of the space formed

20 by the opposed inclined faces of the rails *a'* *b'* and the faces *f'-t* and *g'-q* of the members A B, and by the normal position of the apex of the notch in the pawl being not only coincident with said passage but vertically

25 beneath the axis of movement of said pawl, so that even if a wire or other implement were entered between the rails and then between the members A and B and made to catch on the pawl a pull on such

30 implement would then result in no movement of the pawl. The form and disposition of the hook-proper of hook *o* and the notch of the pawl when engaged with each other are such that the apex of the former

35 engages at the apex of the latter and the point of engagement is vertically beneath

the axis *h* of the pawl, so that a force applied to open one of the sashes when interlocked by the device tends to produce no movement of the pawl on its pivot.

Occasionally the upper sash will be left slightly lowered so that interlocking would not take place on closing the lower sash. The flaring of member B as described affords in that case a hand-hold whereby by 45 means of said member to move the upper sash to fully closed position.

v in Fig. 3 is a stop to limit the unlocking movement of the pawl or lever *i*.

Having thus fully described our invention, what we claim as new and desire to secure by Letters Patent is:—

A sash-lock including, in combination, a pair of members adapted to be respectively secured on the top surfaces of the meeting 55 rails of two sashes and arranged to face each other and form a narrow space between them when said rails face each other, a hook pendently pivoted in the relatively inner member and having a V-shaped hook notch 60 normally in substantially vertical coincidence with its pivot and in substantial coincidence at its apex with said space when said members are so arranged, the other member having an inwardly projecting 65 catch shoulder engaged by said hook when said members are so arranged.

In testimony whereof we affix our signatures.

WILLIAM A. LAUFER.
ANDREW KUFTA.
